UNITED STATES PATENT OFFICE.

JOHN T. CROWLEY, OF BEACON FALLS, CONNECTICUT, ASSIGNOR TO THE BEACON FALLS RUBBER SHOE COMPANY, OF BEACON FALLS, CONNECTICUT, A CORPORATION OF CONNECTICUT.

GAITER.

1,124,710.

Specification of Letters Patent. Patented Jan. 12, 1915.

Application filed July 29, 1914. Serial No. 853,826.

To all whom it may concern:

Be it known that I, JOHN T. CROWLEY, a citizen of the United States of America, residing in Beacon Falls, in the county of New Haven and State of Connecticut, have invented certain new and useful Improvements in Gaiters, of which the following is a specification.

This invention relates to gaiters or artics 10 and aims to provide certain improvements therein.

The invention is particularly directed to children's gaiters or other gaiters in which it is desired to have a small ankle portion 15 as compared with the size of the foot.

In the ordinary construction of arctic the upper is composed of side pieces of cloth and a front piece, the edges of which are vulcanized to the side pieces. At the upper 20 portion of the front piece it is cut downwardly, and a gore-shaped piece is inserted. This gore-shaped piece enlarges the upper dimension of the front piece, so as to enable the foot to be inserted in the gaiter. 25 This construction is usually satisfactory in the case of adults' gaiters, but when applied to childrens' gaiters it is found that if there is sufficient fullness in the upper part of the gaiter to enable the gaiter to be removed 30 from the vulcanizing form or last the gaiter is too large for the ankle of the child. All previous attempts to reduce the dimension of the top of the gaiter have been ineffective, since it is then found impossible to remove 35 the gaiter from the last or mold.

According to the present invention I introduce a separate gore, or fold into the top of the gaiter, and preferably in the gore-shaped piece now commonly used. By this 40 construction I enlarge the possible capacity of the arctic for extension. The other portions of the top may hence be reduced in size so as to snugly fit a relatively small ankle. Preferably the additional gore provided by 45 the present invention is of cheap material, since it is not visible when the arctic is in use. At the same time it provides an enclosure which is more or less water-proof up to the top of the gaiter. Other features of 50 improvement are hereinafter more fully described.

Referring to the drawings, — Figure 1 is a perspective view of the improved construc-

tion. Fig. 2 is a front perspective. Fig. 3 is a detail view.

Referring to the drawings, let A indicate the sole portion B B' the sides, and C the front. These parts are usually formed of cloth, in some instances rubberized, and extend around the sole portion A to the top of the arctic. Usually a rubber coating or facing D is applied around the bottom of the arctic. The edges E E' of the front portion C are vulcanized to the forward edges of the side portions B B' in such manner as to fold backwardly, and in order to obtain a greater fullness at the top of the front portion it has been cut along the edges F F', and a gore-shaped piece inserted in the opening thus formed. As before stated, it is found in practice, however, that the additional fullness thus obtained is not sufficient to enable the arctic to be removed from the mold unless the sides B B' are so large as to make the top of the arctic too full for slender ankles.

According to the present invention I provide an additional piece in the front of the arctic, and preferably this piece is of segmental form and is inserted in the gore-shaped piece just referred to. In the drawing the gore-shaped piece is designated by the letters G G', the piece being practically separated into two parts. The segmental portion H provided by the present invention is shown as vulcanized to the inner or separated edges of the gored halves G G'. The piece H is folded so that its edges lie near its middle while its rear portion H' lies flat along the ankle.

When the arctic is closed by the usual buckles or otherwise, the edges of the lower halves G G' lie together so that the appearance of the arctic is not substantially different from that of the ordinary construction.

It is customary to provide the arctic with a fleece lining which is substantially continuous when the arctic is in place on the foot. The segmental piece H need not, however, be made of lined material or other expensive material, since the parts G G' overlap it completely when the arctic is closed.

In Fig. 3 is illustrated the segment H in its extended position. In Fig. 1 in dotted lines I have shown the top of the arctic in its condition of greatest extension. In this

condition no difficulty is encountered in removing the arctic from the mold or the last, even though the sides B B' be shortened from front to rear. The increased capacity of the top of the arctic is also of value in drawing it in place over the shoe and in removing it.

While I have shown and described one form of the invention, it will be understood that I do not wish to be limited thereto, since various changes may be made therein without departing from the invention.

The manner of forming the segmented portion H in the adjacent portions of the article of foot wear is described and claimed in my co-pending application for Miner's shoe, Serial No. 859,600, filed September 1st, 1914.

What I claim is:—

1. An arctic having front and side portions, and a gore in the front portion, and a segmental foldable piece inserted in said front portion and connected to said gore. 20

2. An arctic having front and side portions, a gore-shaped piece in said front portion, said gore-shaped piece being cut at its middle, and a foldable segmental portion connected to said gore at said cut. 25

In witness whereof, I have hereunto signed my name in the presence of two subscribing witnesses. 30

JOHN T. CROWLEY.
